(57) **CLAIM**

The ornamental design for a display panel of a programmed computer system with a graphical user interface, as shown and described.

DESCRIPTION

FIG. 1 is a first image of a display panel of a programmed computer system with a graphical user interface;
 FIG. 2 is a second image thereof;
 FIG. 3 is a third image thereof;
 FIG. 4 is a fourth image thereof;
 FIG. 5 is a fifth image thereof;
 FIG. 6 is a sixth image thereof;
 FIG. 7 is a seventh image thereof;
 FIG. 8 is an eighth image thereof; and,
 FIG. 9 is a ninth image thereof.

The appearance of the transitional image sequentially transitions between the images shown in FIG. 1-9. The process or period in which one image transitions to another image forms no part of the claimed design.

The broken line showing of a display panel with graphical user interface is included for the purpose of illustrating portions of the article and forms no part of the claimed design.
